UNITED STATES PATENT OFFICE.

SIDNEY SMITH, OF BRIDGEPORT, ASSIGNOR TO THE WILLIAM ROGERS MANUFACTURING COMPANY, OF HARTFORD, CONNECTICUT.

DESIGN FOR A SPOON, FORK, &c.

SPECIFICATION forming part of Design No. 24,298, dated May 14, 1895.

Application filed March 4, 1895. Serial No. 540,529. Term of patent 7 years.

To all whom it may concern:

Be it known that I, SIDNEY SMITH, a citizen of the United States, residing at Bridgeport, in the county of Fairfield and State of Connecticut, have invented and produced a new and original Design for Spoons, Forks, and Similar Articles; and I do declare the following to be a full, clear, and exact description of the same, reference being had to the accompanying drawings, forming a part thereof.

Figure 1 is a plan view of the upper or obverse side of a spoon embodying my novel design, the outlines of a fork appearing in dotted lines; and Fig. 2 is a plan view of the back or reverse side of a spoon embodying my novel design, the outlines of a fork appearing in dotted lines.

The leading features of my novel design consist of the shape and ornamentation of the handle as herein shown and described. The outlines of both edges of the handle are the same. At the tip is a rounded point 1. Below the tip the outlines of both edges show first a convex curve 2 running out in a concave curve 3 which in turn swells into a second convex curve 4, the latter running into a slightly concave curve 5 which itself runs

out in the shank. On the obverse side are two plain surfaces denoted by 7. These surfaces are separated by ornamentation of conventional flowers denoted by 9. At the end of the handle and where the handle runs into the shank and where the shank runs into the bowl of a spoon or body of a fork I provide conventional foliate ornamentation denoted 30 by 10. At the edges and on the shank on the obverse side I provide ornamentation consisting of raised bosses denoted by 11. On the reverse side the center is a plain surface denoted by 12. Around the edges is an ornamental groove 13, and at detached places I provide conventional foliate ornamentation 35 denoted by 14.

What I claim is—

The design for a handle for spoons, forks 40 and similar articles substantially as shown and described.

In testimony whereof I affix my signature in presence of two witnesses.

SIDNEY SMITH.
